UNITED STATES PATENT OFFICE.

FRITZ ACH, OF MANNHEIM, GERMANY, ASSIGNOR TO C. F. BOEHRINGER & SOEHNE, OF WALDHOF, GERMANY.

ALKYLOXYCHLOROPURIN AND METHOD OF PREPARING SAME.

SPECIFICATION forming part of Letters Patent No. 654,120, dated July 24, 1900.

Original application filed February 18, 1898, Serial No. 670,847. Divided and this application filed July 22, 1899, Serial No. 724,838. (No specimens.)

To all whom it may concern:

Be it known that I, FRITZ ACH, a citizen of the Empire of Germany, residing at Mannheim, Germany, have invented certain new 5 and useful Improvements in Alkyl-Oxy-Purins and Methods of Preparing Same; and I do hereby declare the following to be a full, clear, and exact description of the invention, such as will enable others skilled in the art to which 10 it appertains to make and use the same.

This invention relates to the manufacture of alkylized oxy-chloropurins, and in particular to trialkylized oxy-purins.

In carrying out my invention I start from 15 3-alkyl-chloroxanthins, otherwise known as "3-alkyl-8-chloro-2-6-dioxy-purins," such as 3-methyl-chloroxanthin, which compound, together with its mode of preparation, has been described and claimed in my Letters 20 Patent of the United States No. 631,757, dated August 22, 1899, (of which this is a divisional application,) this 3-alkyl-chloroxanthin being submitted to the action of alkylizing agents in order to obtain the new compounds.

Before proceeding with the specification I will state that I have herein adopted the nomenclature and system of numbering the carbon and nitrogen atoms of the purin-nucleus which has been introduced by Prof. 30 Emil Fischer and described in *Berichte der Deutschen Chemischen Gesellschaft*, Vol. 30, p. 549. According to this system the purin-nucleus is arranged and its atoms are numbered thus:

According to this nomenclature and system 45 xanthin—*e. g.*, whose formula is:

is denominated 2-6-dioxypurin and chloro-caffein, having the formula:

is 1-3-7-trimethyl-8-chloro-xanthin or 1-3-7-trimethyl-8-chloro-2-6-dioxy-purin.

In my aforesaid application I have described and claimed generically the method of proceeding from alkyl-uric acids having no alkyl in the position 9, first, to alkylized chloro-xanthins by the agency of phosphorus-oxy-chlorid and then from such alkylized chloro-xanthins to higher alkylized products by alkylization and reduction or vice versa. In that application I have also described and claimed the more specific method of applying the above treatment to 3-alkyl-uric acids and more particularly 3-methyl-uric acid. Among other things I claim in that application the method of preparing 3-alkyl-chloroxanthin and specially 3-methyl-chloro-xanthin from 3-methyl-uric acid and also the said new compound 3-methyl-chloro-xanthin. Such matter is therefore not claimed herein; but the invention forming the subject-matter of the present application consists in the preparation of alkylized oxy-chloropurins and specifically 3-methyl-1-7-diethyl-2-6-dioxy-8-chloropurin and also in the method of proceeding from this new compound to a chlorin-free product by reduction and in this new compound itself.

In order to fully disclose my invention, I will first describe the method of preparing the starting material 3-methyl-chloro-xanthin from 3-methyl-uric acid, it being understood that this method and the resulting compound are not herein claimed, since they form the subject-matter of the claims of my aforesaid application.

Preparation of 3-methyl-chloro-xanthin 100
from 3-methyl-uric acid.—One part of anhydrous 3-methyl-uric acid is added to five parts, by volume, of phosphorus-oxy-chlorid and heated under pressure (*e. g.*, in a digester) to from 130° to 140° centigrade and maintained 105 at this temperature for from three to four

hours, the mass being steadily agitated. The resulting clear reddish-brown solution is then evaporated *in vacuo* for the purpose of completely removing the phosphorus-oxy chloride. The brownish residue, which has a tough varnish-like consistency, is thereupon brought into solution by boiling the same with about five times its quantity of alcohol or water. The alcoholic solution, which at 5 first is clear, but soon becomes turbid on account of the precipitation of granular crystalline methyl-chloro-xanthin, is boiled for from two to three hours in a reflux condenser and then allowed to cool. Upon then filtering the methyl-chloro-xanthin remains on the filter as a yellow granular crystalline mass. The filtrate is then evaporated, whereby a second crystallization ensues, resulting in a further yield of the above product, methyl-chloro-xanthin. The crude product so obtained is brought into solution with dilute alkali, such as two-per cent. potash lye, treated with animal charcoal or other decolorizing agent, and finally precipitated with 15 dilute sulfuric acid. On cooling the new compound is obtained in the form of yellow-hued coarse crystals, from whose analysis are obtained figures which show the formula of this compound to be $C_6H_5N_4O_2Cl + H_2O$. Its structural formula is found to be:

such formula being established by the fact of 40 the ready conversion of this compound into chloro-caffein. (See under II^a.) I therefore designate this new compound as 3-methyl-chloro-xanthin or 3-methyl-8-chloro-xanthin. The tenaciously-adhering yellow tint, which 45 is very difficult of removal, has no influence on the percentage composition of the product. Absolute decoloration of the methyl-chloro-xanthin may be attained by thoroughly boiling it with a large quantity (thirty parts to 50 one part of the methyl-chloro-xanthin) of acetone. The xanthin is thereby gradually brought into solution, while the adhering coloring-matter remains undissolved. Upon cooling, after such solution is effected, the 55 methyl-chloro-xanthin crystallizes in anhydrous fine colorless shining foliated crystals or scales. 3-methyl-chloro-xanthin is soluble in about two hundred and fifty parts boiling water, and on cooling the solution slowly the 60 same crystallizes therefrom in coarse needles, which under the microscope are found to be elongated flat prisms and which contain one molecule of water of crystallization. This water of crystallization escapes on protracted 65 heating at 120° centigrade. It is difficult of solution in boiling alcohol, in acetone, acetic ether, benzene, or chloroform, readily soluble

in dilute alkalis, in ammonia, and soda or potash solutions. It is equally soluble in concentrated sulfuric acid and fuming hydrochloric acid. From a solution in the latter the original product is precipitated by water on standing for some time. Heated with chlorin-water or with dilute nitric acid it gives a strong murexid reaction. An ammoniacal solution of the same added to an ammoniacal silver solution yields a gelatinous silver salt which remains unchanged on boiling. 3-methyl-chloroxanthin has no melting-point; but on being rapidly heated 80 it begins to turn yellow at 320° centigrade, and at about 345° centigrade it decomposes with effervescence. From this body 3-methyl-chloroxanthin the new compound 3-methyl-1-7-diethyl-2-6-dioxy-8-chloropurin or 3-methyl-diethylchloro-xanthin is made, as follows:

Preparation of 3-methyl-1-7-diethyl-2-6-dioxy-8-chloropurin from 3-methyl-chloroxanthin.—Four parts, by weight, of 3-methyl-chloroxanthin are dissolved in twenty-three parts, by volume, of double-normal potash-lye (potassium-hydrate solution) and diluted with twenty parts, by volume, of alcohol. Six and one-half parts, by weight, of ethyl-iodid are then added and the whole is boiled for from three to four hours with reflux. The mass is then allowed to cool, when it solidifies in the form of a pulp or fine felted needles. These are then separated by filtration, redissolved in boiling water and recrystallized therefrom. The fine acicular crystals so obtained have the composition indicated by the formula $C_{10}H_{13}N_4O_2Cl$, or structurally expressed:

The reaction to which the formation of the new compound is due proceeds according to 115 the equation:

This new compound with chlorin-water gives a strong murexid reaction. Its melting-point

is 136° centigrade. It is moderately soluble in boiling and difficultly soluble in cold water. It dissolves readily in hot alcohol and in cold acetone or chloroform. It is also readily soluble in fuming hydrochloric acid, being precipitated from such solution by water. It will be noted that its structure closely resembles that of chloro-caffein, the only difference being that in lieu of the methyl groups in the positions 1 and 7 in the latter compound it has substituted ethyl groups.

20 Chloro-caffein or 1-3-7-trimethyl-8-chloro-xanthin or 1-3-7-trimethyl-8-chloro-2,6-dioxy-purin.

The new trialkyl-dioxy-chloropurin or trialkyl-chloroxanthin just described may be reduced to a chlorin-free compound by the following method:

Preparation of 3-methyl-1-7-diethyl-2-8-dioxy-purin.—This new body is obtained by reduction of 3-methyl-1-7-diethyl-2-6-dioxy-8-chloropurin or 3-methyl-1-7-diethyl-8-chloroxanthin, which has been described under head II³. If one part, by weight, of this chloroxanthin be heated with ten parts, by weight, of fuming hydriodic acid to 90° centigrade, solution is speedily effected. The heating is then continued on a boiling-water bath so long until, with the addition of phosphonium-iodid in sufficient quantity to take up the liberated iodin, a clear solution is formed. This solution is then evaporated to dryness, and the crystalline residue is taken up with water and supersaturated with alkali. Through this treatment the new base separates as a colorless oil, which very soon congeals, forming fine acicular crystals. The base is then extracted with a suitable vehicle, such as chloroform or ether, whereupon the extract is evaporated and the colorless residue recrystallized from benzene. From the benzene solution, to which ligroin is preferably added, the 3-methyl-1-7-diethyl-2-6-dioxy-purin crystallizes in the form of splendidly-developed vitreous colorless prisms whose analysis gives figures which correspond well to the formula $\text{C}_{10}\text{H}_{14}\text{N}_4\text{O}_2$.

55 The structural formula of the base is:

65 The reducing process is expressed in the equation:

As a xanthin, this new body with chlorin-water gives a strong murexid reaction. It melts at from 127° to 128° centigrade. It is readily soluble in water, alcohol, chloroform, benzene, ether, and concentrated hydrochloric or sulfuric acid. From an aqueous solution this mass is precipitated by concentrated alkaline lyes as a colorless oil which soon solidifies to a crystalline mass.

90 3-methyl-chloro-xanthin and the process of preparing it, while described for the purposes of a full disclosure, are not herein claimed, since they are covered in my Patent No. 631,757 aforesaid.

95 What I claim, and desire to secure by Letters Patent, is—

1. The process which consists in submitting 3-alkyl-chloro-xanthin to the action of an alkylizing agent. 100
2. The process which consists in heating 3-methyl-chloro-xanthin with potash-lye and alcohol, together with ethyl-iodid.
3. The process which consists in dissolving 3-methyl-chloro-xanthin in potash-lye and 105 alcohol, adding ethyl-iodid and boiling in a reflux cooler, all in the proportions and under the conditions substantially as stated.
4. The process which consists in subjecting 3-methyl-1-7-diethyl-2-6-dioxy-8-chloro-purin 110 to the action of a reducing agent.
5. The process which consists in heating 3-methyl-1-7-diethyl-8-chloro-xanthin together with hydriodic acid and phosphonium-iodid. 115
6. The process which consists in the following steps: heating 3-methyl-1-7-diethyl-8-chloro-xanthin together with fuming hydriodic acid in the proportions and temperature given; continuing the heating on a boiling-water bath and adding phosphonium-iodid until a clear solution is formed, then evaporating this solution to dryness, taking up the crystalline residue with water and supersaturating with alkali; then extracting with a 120 suitable vehicle and evaporating the extract and, finally recrystallizing the colorless residue.
7. The process which consists in submitting 3-alkyl-chloro-xanthin to an alkylizing agent 130 and then acting upon the resultant trialkyl-dioxy-chloro-purin with a reducing agent.

8. The process which consists in heating 3-methyl-chloro-xanthin with potash-lye and alcohol together with ethyl-iodid and then treating the resultant product with hydriodic acid and phosphonium-iodid.

9. As a new chemical compound, 3-methyl-1-7-diethyl-2-6-dioxy-purin, having the formula above given, which is soluble in water, alcohol, chloroform, ether and concentrated hydrochloric or sulfuric acid, which is precip-

itated from an aqueous solution as a colorless oil by strong alkaline lyes, which crystallizes in the form of vitreous, colorless prisms and melts at about 127°, centigrade.

In testimony whereof I affix my signature 15 in presence of two witnesses.

FRITZ ACH.
